ATTORNEY.

UNITED STATES PATENT OFFICE

PRESTON M. BRUNER, OF SAN FRANCISCO, CALIFORNIA

IGNITION MEANS FOR INTERNAL COMBUSTION ENGINES

Application filed December 9, 1929. Serial No. 412,729.

The present invention relates to improvements in internal combustion engine ignition systems and has for its primary object the provision of means for the ignition of compressed charges in the cylinders of the engine through the media of a previously ignited charge.

In present ignition systems, spark plugs are employed to fire the compressed charges of gas in the engine cylinders and this system, generally, is the most vital part of the power unit and often causes considerable trouble due to shorting of the wiring, battery troubles, dead or fouled spark plugs and various other causes.

In the present system, all spark plugs are eliminated and the compressed charges in the cylinders are fired in sequence by means of a previously fired hot charge of gas.

In order that the present system may be operated, it is necessary that electrical means be first employed to ignite a compressed charge and this function is accomplished by the use of a hot wire which is preferably constantly energized.

In general, the device of the present invention comprises an incased timing rotor having ports therein, adapted, when the engine is running, to continuously by-pass, or transfer, a charge of hot gas from a firing cylinder to the next successive cylinder having a compressed charge therein in readiness for firing, to fire that particular compressed charge.

The system of the present invention, of course, requires the use of electrical ignition means, as hereinbefore stated, and this means may consist of a single spark plug, or a hot wire, preferably the latter, in order that the engine may be started initially. However, so soon as the first cylinder, which may be any one of the full complement, is fired, the system becomes automatic in effect, and the electrical ignition means may be then de-energized.

The most important object of the invention is the provision of a simple and efficient ignition system for internal combustion engines, such as motor-vehicle and aeroplane engines, in which the firing of the compressed

charges in the cylinders thereof is accomplished by the introduction of a portion of a hot charge of gas from a preceding cylinder into succeeding ones in sequential order of firing.

Another object of the invention is the provision of an ignition system of the class indicated which eliminates the use of spark plugs in each cylinder of the engine, thereby rendering the system much more reliable and more efficient generally.

Still another object of the invention is the provision of an ignition system that is especially adaptable to aeroplane engines, since such a system avoids to a large extent the possibility of failure of the electrical ignition means at crucial times.

The invention possesses other objects and features of advantage, certain of which, together with the foregoing, will be more fully set forth in the following description of the preferred form of the invention, and be illustrated in the accompanying drawing forming part of this specification, in which similar reference characters refer to like parts, throughout. It is to be understood that I do not limit myself to the showing made by the said drawing and description, as I may adopt variations of the preferred form within the scope of my invention as set forth in the appended claims.

The accompanying drawing illustrates the invention, in which:

Figure 1 is a diagrammatic plan view of an internal combustion engine, showing the improved system as applied to a motor-vehicle engine;

Figure 2 is an elevation illustrating the piping system leading to the various cylinders of the engine.

Figure 3 is a considerably enlarged plan view illustrating the rotor and rotor casing per se, the view being indicated by the line 3-3 in Figure 4;

Figure 4 is a vertical sectional view of the rotor and rotor casing and shows the electrical means for initially igniting a charge of compressed gas as delivered to the rotor transfer port; and

Figure 5 is a broken plan view of the cover.

plate for the rotor casing and illustrating the electrical connections for energizing the hot wire in the firing chamber.

Referring to the drawing in detail, and particularly to Figure 1 thereof, it will be observed that the device has been shown in the said drawing as applied to a motor-vehicle engine 10, comprising the usual cylinder block 11, cylinders 12, and the usual spark plug openings 13.

In the application of the present system to new motors it would be the preferable practise to encase the rotor in the cylinder block, however, as here shown, the device has been illustrated as a separate unit and as externally fitted to the motor block.

The timing distributor, or rotor, is indicated, generally, by the numeral 14, and consists of a circular casing having an interiorly finished chamber 15 adapted for the reception of the timing rotor proper 16.

The engine, as herein illustrated, has a firing order of 1, 5, 3, 6, 2, 4, however, it is to be understood that the device may be adapted to any engine firing order, as embodied in various engine constructions.

The casing of the rotor is provided with a plurality of radially arranged and equally spaced bosses 17, 18, 19, 20, 21 and 22, each having a port communicating with the interior of the rotor chamber, as clearly indicated in Figure 3. This arrangement, of course, is for a six cylinder engine, and, in the construction shown, a pipe 23, leads to No. 1 cylinder, pipe 24 leads to No. 5 cylinder, pipe 25 to No. 3 cylinder, pipe 26 to No. 6 cylinder, pipe 27 to No. 2 cylinder and pipe 28 to No. 4 cylinder.

The rotor is provided axially thereof with a bore 29, which is tapped for the reception of a threaded thimble 30, in which thimble is mounted a porcelain, or other non-conducting element 31, having arranged thereon a pair of contact rings 32 and 33 adapted for rotating contact with resilient brushes 34 and 35 suitably positioned within a casing 36 which may be composed of any well known insulating material, such as hard rubber.

The rotor casing 14 is provided with a spider 37 consisting of a ring 38 which supports the casing 36 carrying the brushes 34 and 35, the spider 37 being secured to the rotor casing 14 in any suitable manner, as by means of screws 39, as clearly indicated in Figure 5.

The rotor is preferably air cooled and provision is made for cooling the same by means of a plurality of fan blades 40 and an additional fan 41 mounted upon the driving shaft 42, as clearly indicated in Figure 4.

The rotor also embodies a transferring or by-passing port 43, which may be arcuate or V-shaped in configuration and which communicates with the central bore 29 thereof

and any pair of the pipes 23 to 28 inclusive of the system.

Ignition means is provided in the central chamber 29 and, as here shown, consists of a resistance coil 44 which is electrically connected in circuit to the contact rings 32 and 33, which in turn, are electrically connected by means of binding posts included in a suitable circuit 45 controllable by means of a switch 46, as clearly indicated in Figure 1.

The rotor may be driven by means of a drive shaft 47 having geared connection to the shaft 42 and operated through the agency of any suitable moving part of the engine and geared to rotate at one-half of the speed of the crank-shaft thereof.

In operation:

Assuming that the engine is dead and that it is desired to start the same, the usual starter, of course, being used to turn the engine over, the while the ignition element has been energized by any suitable electrical means to produce a highly heated resistance element, the rotor will be rotated accordingly and the port 43 will follow around until a particular cylinder now under compression is fired by said ignition element, this firing of the charge being accomplished, by virtue of the fact that a portion of the compressed charge from said cylinder has been forced into any particular line of the system.

The various lines 23, 19, 25, 26, 27 and 28 lead from the spark plug openings in the engine block to the rotor casing and are secured to the said engine block in any suitable manner.

Due to the extreme heat of the exploded charge at the instant of firing, and this hot charge being injected into the rotor at this high temperature and transferred to the next cylinder under compression, it is assured that these charges of hot gases will ignite the highly inflammable gases under compression, the firing being in sequential order.

Having thus described my invention, I claim and desire to secure by Letters Patent of the United States, the following:

1. An ignition device for an internal combustion engine comprising a rotor having a central firing chamber electric ignition means projecting into said chamber and secured to said rotor, a circular casing for said rotor, a spider secured to the periphery of said casing, contacts carried by the spider and adapted to energize the ignition means, said casing having a series of openings therein spaced peripherally thereof, said rotor having a gas passage comprising two radial arms communicating with the firing chamber and adapted to establish communication between two adjacent openings upon rotation of the rotor and means for rotating the rotor.

2. In an ignition device for internal combustion engines, as claimed in claim 1, cool-

ing means forming a part of the rotor and rotating therewith.

3. In a device of the class described, a timing element comprising a rotor, a casing for said rotor, a plurality of pipe lines communicating therewith, said rotor embodying an axial firing chamber, a spark plug in said chamber, a radially disposed V-shaped port communicating respectively with said spark plug chamber and two of said pipe lines, and means for rotating said rotor.

4. An ignition device for an internal combustion engine, comprising a rotor, a casing for said rotor, a plurality of radially disposed gas passages leading outwardly from said casing, a gas passage through said rotor, said last named gas passage having two branches terminating in spaced openings in the periphery of the rotor, the spaces between the openings being substantially the same as the spaces between the gas passages in the casing, and means for rotating the rotor.

5. In an ignition device for an internal combustion engine, a rotor, an axial firing chamber in said rotor, a single gas passage in said rotor comprising two radial passages communicating with said firing chamber and terminating in the periphery of the rotor, a casing having a plurality of gas pipes connected thereto and leading from the interior thereof, said gas pipes being adapted to be placed in communication with the cylinders of said engine, the distance between the adjacent gas pipe connections being substantially the same as the distance between the terminals of the branches of the gas passage, and means for rotating the rotor.

In testimony whereof, I hereunto affix my signature.

40 PRESTON M. BRUNER.
